Attorney:

UNITED STATES PATENT OFFICE.

FREDERICK H. CLARK, OF PROVIDENCE, RHODE ISLAND, ASSIGNOR TO IRA P. SMITH,
OF WORCESTER, MASSACHUSETTS.

CONTAINER-RECORD.

1,277,696.

Specification of Letters Patent. Patented Sept. 3, 1918.

Application filed August 20, 1917. Serial No. 187,074.

To all whom it may concern:

Be it known that I, FREDERICK H. CLARK, a citizen of the United States, residing at Providence, in the county of Providence and State of Rhode Island, have invented 5 certain new and useful Improvements in Container-Records, of which the following is a specification.

My invention relates to a device or means 10 for conveniently identifying and recording the dispensing of narcotics or opiates.

A Federal enactment requires the physician or other dispenser of drugs which contain a narcotic, to record the quantity of the 15 narcotic in the drug dispensed on each occasion, as well as to preserve such record for at least two years. The time and labor thus involved when the physician personally dispenses a drug is excessive even if he should 20 know the quantity of the narcotic in the composition without a search for the formula of it in a drug dealer's catalogue. Further delay is occasioned in identifying a composition in a well filled laboratory, and 25 this is increased when the paper to receive the record is not at hand or misplaced.

The essential objects of my invention are to save the time of the dispenser; to insure an accurate record of every element of the 30 composition containing the narcotic, of the quantity of the composition dispensed, as well as the quantity of the narcotic, and of the date, name and address of the patient, and the dispenser's name; to insure the in- 35 stant availability of the paper to receive the record; to insure a secure and facile attachment of the same to the receptacle; and to attain these ends in an inexpensive and simple construction.

40 In the accompanying drawings which form a part of this specification,

Figures 1 and 2 are front and side elevations respectively of a container embodying my recording device, and

45 Fig. 3 a transverse section of the same on line 3—3 of Fig. 2.

Like reference characters indicate like parts throughout the views.

A container 5, which may be a box, bottle, 50 carton, or other convenient receptacle is in the present instance a bottle preferably having plane or flat sides. In this container is a compound, either liquid or dry, containing as an element an opiate or narcotic. In this

instance the compound or composition is in 55 the form of tablets 6. A strip of paper, fabric, or other flexible material 7 has upon its inner face an adhesive coating 8 such as dry mucilage so that when the latter is moistened the member may be applied to the bottle as 60 a binding strip. This strip embraces the back board 10 of a pad 11, oblong in outline, and holds the board or strip tightly against the face of the bottle. The pad comprises 65 in addition to the strip 10, a body portion of superposed oblong leaves 12 attached at one of their narrower ends by staples 13 or otherwise to the back strip, and provided preferably near their tops with a transversely disposed series of piercings 14 to 70 facilitate severance of the leaves along the line of piercings. The pad itself may be directly fixed to the receptacle if desired.

Upon the face of each leaf about a third 75 of the length of the leaf downwardly from its top is a transverse line 16 inclosing an area 17 adapted to receive the data 18 constituting the formula of the composition of the tablets 6. The area below the line 16 has several longitudinally disposed lines for additional data, namely, a line 20 for reception of the date the sale was made, a line 21 for the name of the patient, a line 22 for his address, a line 23 for the name of the dispenser, and a line 24 for the quantity of tablets dis- 80 pensed.

It will be noted that the formula 18 is 85 permanently printed, as well as are the words "Date," "Patient," "Address" and "Quantity," so that when one or more tablets are dispensed the operator has only to insert the obvious incidental data on lines 20, 21, 22, and 24 to have a complete record, and after such insertion the leaf is torn off and preserved.

I claim:

1. In a device of the type set forth, the combination of a container adapted to carry a narcotic compound, a pad comprising a back strip and superposed detachable leaves 100 provided with a formula of the compound, and an adhesive strip engaging the container and embracing the strip.

2. In a device of the type set forth, the combination of a container provided with flat faces, a back strip resting upon one of the faces, superposed leaves attached at one end to the strip, and a flexible strip attached 105

at its ends to the container and embracing the back strip, each leaf being provided with a formula.

3. In a device of the type set forth, the combination of a container adapted to carry a narcotic compound, a pad comprising a back strip resting on the container and superposed leaves detachably engaging the back strip, a flexible strip engaging the back

strip and the container, said leaves being 10 provided with a uniform formula of the compound, and with lines adapted to receive entries of a date, a name, an address, and a quantity of the compound.

In testimony whereof I have affixed my 15 signature.

FREDERICK H. CLARK.

Copies of this patent may be obtained for five cents each, by addressing the "Commissioner of Patents, Washington, D. C."
